DESCRIPTION

FIG. 1 is a top perspective view of a charger embodying our new design;

FIG. 2 is a bottom perspective view thereof;

FIG. 3 is a front view thereof;

FIG. 4 is a back view thereof;

FIG. 5 is a side view thereof;

FIG. 6 is another side view thereof;

FIG. 7 is a top view thereof; and,

FIG. 8 is a bottom view thereof.

Broken lines, where shown, are used to illustrate portions of the charger that form no part of the claimed design.
